BOOK PROTECTOR

Robert Perry Sharp, Uvalde, Tex., assignor to
 Sharp & Company, Uvalde, Tex., a corporation
 of Texas

Application May 12, 1937, Serial No. 142,255

1 Claim. (Cl. 281—34)

This invention relates to book cover enclosures or protectors, and more particularly to an enclosure or protector formed from a sheet or sheets of suitable pliable and foldable material.

5 An important object of the invention is to provide a protector which will give adequate protection to the corners of a book cover enclosed thereby and will not bulge nor wrinkle.

Another object is to provide a protector which 10 is easy to fit to book covers of various sizes.

Still another object is to provide a protector which may initially comprise a rectangular sheet of suitable material but may be easily cut into, without wasting any of the material, to provide a 15 covering for the covers of a book.

Another object is to provide a book cover protector, containing flaps which may be pasted, yet the construction is such that, in opening and closing the book, the pasted flaps will not tear 20 loose nor break away.

Yet another object is to provide a book cover protector, containing inwardly projecting flaps, which flaps will not tend to tear the book covers loose from the book nor tear the covers away from 25 the backs.

Other objects and advantages of the invention 30 will be apparent during the course of the following detailed description, taken in connection with the accompanying drawing, forming a part of this specification and in which drawing:—

Figure 1 is a perspective view of the flattened blank from which the protector is made, with a book, to which the blank is to be fitted, in place and showing the first step of fitting the blank to 35 the book cover.

Figure 2 is a perspective view showing the next step of fitting the blank to the cover.

Figure 3 is a perspective view showing a subsequent step, after the book is temporarily removed 40 and certain portions of the protector folded and others parted to form flaps.

Figure 4 is a perspective view showing the book again in position with portions of the flaps in 45 place.

Figure 5 is a perspective view illustrating a method of attaching certain flaps of the protector together.

Figure 6 shows the protector in its final position about the book covers.

In the drawing, wherein for the purpose of illustration is shown a preferred embodiment of the invention and wherein similar reference characters designate corresponding parts throughout 55 the several views, the letter A may designate gen-

erally a book and the letter B the novel protector or enclosure therefor.

The book A, shown by way of example, is one including a conventional front cover 10 having an outer face 11 and an inner face 12, a rear cover 13 having an outer face 14 and an inner face 15, and a back 16. While the term "book" is employed, it should be understood that the novel protector may be employed in protecting magazine covers, snap shot album covers, portfolio covers and the like.

As for the novel protector or enclosure B, this initially comprises one or more sheets of suitable material. In the example shown, one sheet 20 is employed and it is preferred to employ but one 15 sheet in order to cover or protect each book. This sheet is preferably of easily foldable material, such as paper, cardboard, canvas, leather or the like, and is rectangular, having substantially parallel side edges 21 and 22, and substantially 20 paralleling end edges 23 and 24, joining the edges 21 and 22.

The sheet 20 is adapted to be initially folded in the well known or conventional way of turning inwardly the side portions 25 and 26 so that, when 25 these are folded flat along the dotted lines 27 and 28 which define the top and bottom edges respectively of the protector, the width of the folded sheet 20 is substantially that of the height of the covers of the book A. These fold lines 27 30 and 28 may be determined as clearly shown in Figure 1, which illustrates a well known method.

Next, the folding of the end portions 29 and 30 of the sheet 20 is made, as in conventional practice, by placing the partly folded sheet about the 35 book, as shown in Figure 2, and folding the end portions 29 and 30 inwardly along the determined fold lines 31 and 32, shown in Figure 3. These dotted lines 31 and 32 define the end edges of the protector as well as the inner longitudinal 40 ends of the end portions 29 and 30.

From this point, there is a radical departure from the conventional, for each of the side portions 25 and 26 are divided into five separate sections or flaps 33 to 37 inclusive, as shown in 45 Figure 3, by suitable slits extending inwardly from the side edges 21 and 22. These slits extend inwardly to the fold lines 27 and 28.

Sections 33 and 37 are substantially alike in area and may be termed the outermost sections. 50 One section 33 is defined by a portion of the side edge 21, a portion of the fold line 27 and one of said slits, the other section 33 is defined by a portion of the side edge 22, a portion of the fold line 28 and one other of the slits aligning with the 55

slit just mentioned. One section 37 is defined by a portion of the end edge 21, a portion of the fold line 27, and a third slit, while the other section 37 is defined by a portion of the end edge 23, 5 a portion of the fold line 28, and a fourth slit, aligning with the third slit mentioned. It should be noted that the width of these sections 33 from the end edge 24 to their boundary slits, is such that a portion of the fold line 32 extends lengthwise of the section 33, and the width of the similar sections 37 are such that a portion of the fold line 31 extends lengthwise of the sections 37.

The sections 35 are located midway of the end edges 23 and 24 and are wider than the width of 15 the book back 16 so that if folds, indicated by parallel dotted lines 38^a in Figure 3, were made to accommodate the width of said back 16, portions of these folds would extend lengthwise of the sections 35.

20 Now, as for the sections or flaps 34 and 36, these are substantially alike in area and, due to the location of the slits as heretofore set out and the width of the sections 33, 35 and 37, the width of each of the sections 34 and 36 is less than the 25 width of the covers 10 and 13, although they have substantial width, as shown in Figure 3.

The sections 33 and 37 may be said to be divided into two parts by the fold lines 31 and 32 respectively and that the sections 35 may be said 30 to be divided into three parts by the paralleling fold lines 38^a.

With the protector folded as shown in Figure 3, i. e., with the sections or flaps 33, 35 and 37 folded inwardly and the sections or flaps 34 not folded, 35 the protector presents four substantially right angular indentations 38 in the edges of the sheet, these indentations 38 taking the place of the four corners of the sheet, and a pair of indentations 39 in the side edges of the sheet, midway the ends 40 thereof, the width throughout of each of these indentations 39 being substantially greater than the width of the book's back 16.

With the arrangement as shown in Figure 3, the protector is placed over a book as shown in 45 Figure 4, by folding inwardly along the line 31, the end portion 29 and a part only of the sections or flaps 37 and then folding inwardly, along the line 32, the end portion 30 and a part only of the flaps 33. The outer corners of the cover 10 50 may now be inserted into the pockets joined by the end portion 29 and parts of the flaps 37 and the outer corners of the cover 13 may be inserted into the pockets formed by the end portion 30 and parts of the flaps 33. There is now a single thickness of material against the outer face and three thicknesses of material against the inner face of 55 each cover 10 and 13 at the corners which corners are pocketed in the protector.

By next raising the cover 10 and folding inwardly the flaps or sections 36 against the inner face 12 thereof and overlapping parts of the end portions 29, where an adhesive may be applied, as clearly illustrated, in Figure 5, the end portion 29 and flaps 36 may be secured together.

60 65 In the same way, the cover 13 may be raised

and the remaining portion of the flaps or sections 34 may be folded against the inner face 15 thereof so as to overlap parts of the end portion 30, where an adhesive may be applied in order to secure these overlapping parts to the end portion 30.

5 This incloses the book covers, as is clearly illustrated in Figure 6. From this illustration, it will be seen that the sections or flaps 34 and 36 do not extend in one direction to the juncture of the cover and back, nor extend in the other direction 10 to the outer end edges of the covers. There is, in the first place, no tendency of the edges of the flaps 34 and 36 to bite into the outermost pages of the book, as has been found to be the case where flaps extend across the inner face of a 15 cover to the juncture of such pages and covers, nor is there the tendency to tear the covers from the back. Since the opposite ends of the flaps 34 and 36 do not extend to the outer end edges of the covers, there is no tendency to tearing the 20 former nor are there the objectionable unfolded edges of flaps aligning with the outer edges of the covers.

If the book be stood up, the lowermost edge will be raised from the supporting surface by 25 those portions of the flaps 34 under the cover edges and there will be no wear upon these cover edges.

The extra thickness of material at the corners 30 of the covers protects these corners very materially, yet the construction of the protector is such that the book covers have the necessary play and the book may be removed from its protector and replaced therein if desired.

Very often, the outer faces of book covers are 35 rubbed, in opening and closing the book, by the protectors but it will be noted that in the construction herein disclosed, the covers are spaced slightly from the protector, except at the corners and at the back of the book, so that such wear is 40 minimized.

Various changes may be made to the form of 45 invention herein shown and described, without departing from the spirit of the invention or the scope of the claim.

What is claimed is:

In combination with a book, a book cover protector therefor, provided with a pair of end flaps and a plurality of spaced apart side flaps, said end flaps being folded over the inner faces of the covers of said book, and tabs extending from the ends of said end flaps, said tabs projecting towards each other and lying partly over a section of said end flaps, said tabs being folded partly over part of the inner faces of said book covers at the outer corners thereof and partly folded over a portion of themselves, said side flaps being of less width than the covers of said book and being spaced a substantial distance from the back of said book, said side flaps being folded partly over the inner faces of said covers and partly over said end flaps and being spaced a substantial distance from the free ends of said covers.
